UNITED STATES PATENT OFFICE

153,149

DESIGN FOR A RADIATOR GRILL GUARD

Harold B. Harvey, Carmel, N. Y.

Application October 2, 1947, Serial No. 141,716

Term of patent 3½ years

(Cl. D14—6)

To all whom it may concern:

Be it known that I, Harold B. Harvey, a citizen of the United States, residing at Carmel, in the county of Putnam and State of New York, have invented a new, original, and ornamental Design for a Radiator Grill Guard, of which the following is a specification, reference being had to the accompanying drawing, forming part thereof.

I claim:

The ornamental design for a radiator grill guard, as shown.

HAROLD B. HARVEY.
